UNITED STATES PATENT OFFICE

2,346,741

SAFETY SEAL FOR FIRE EXTINGUISHERS

Fred Fredriksen, Chicago, Ill.

Application March 17, 1943, Serial No. 479,400

5 Claims. (Cl. 299—97)

This invention relates to a safety seal for fire extinguishers and has as its principal object to provide a safety seal which will be relatively simple in construction, economical in manufacture and highly efficient in use.

Another object of my invention is to provide a visible seal the tearing or removal of which will indicate that the fire extinguisher with which it is associated has been used, molested or tampered with.

Still another object of this invention is to provide a rugged seal for fire extinguishers, which seal may be readily removed when the use of the extinguisher is needed.

A further object of this invention is to provide a safety seal for standard hand type fire extinguishers and which seal is flexible to accommodate extinguishers of varied dimensions.

Other objects will appear more fully hereinafter.

This invention consists in the novel combination and arrangement of parts to be hereinafter described and claimed.

The invention will be best understood by a reference to the accompanying drawing in which:

Fig. 1 is a front elevational view of a fire extinguisher having my new safety seal associated therewith;

Fig. 2 is a vertical sectional detail view through my safety seal showing the fire extinguisher in side elevation and a bracket therefor in section as viewed from line 2—2 in Fig. 1;

Fig. 3 is a perspective view of the component parts of my new safety seal;

Fig. 4 is a top plan view of an upper member of my new seal;

Fig. 5 is a top plan view of a lower member of my new seal;

Figs. 6, 7 and 8 show a modified form of my new safety seal, Fig. 6 being a modification of the upper member shown in Fig. 3; Fig. 7 a top plan view of the same; and Fig. 8 a perspective view, looking up at a modified form of bottom member.

Referring to the drawing Fig. 1 shows a fire extinguisher 10 mounted in a rack 11 ready for use. Such racks are placed in various parts of buildings or vehicles in full view and are at all times within reach of the public generally. Because of such availability of these extinguishers they are easily accessible and it is not uncommon that they are occasionally molested and tampered with by unscrupulous persons. It has occurred on numerous occasions when an extinguisher is to be used, that the fluid in it had been removed by a thief, or that the nozzle has been plugged up

by a child or an adult with the mind of a child and as a result the fire extinguisher is worthless when the emergency for which it was provided has arisen. Such defects cannot be seen by a mere glance at the extinguisher and even the persons who are charged with the responsibility of keeping them in working order may in a lax moment overlook the required periodical examination of them. With these conditions in mind I have provided a means for sealing a fire extinguisher in such a manner as to prevent unwarranted tampering without leaving a visible indication that such tampering has taken place.

To accomplish my purpose I provide a seal 25 consisting of a lower cap 13 and an upper cap 14 best illustrated in Fig. 3 which caps 13 and 14 are associated with a wire element 28 and a lead seal 31 for joining the ends of the wire 15 after it has been inserted through the upper and lower caps.

The caps 13 and 14 are preferably formed of a paper pulp which is tough enough to withstand breakage of fibre structure unless a positive effort is made to rip the caps. The lower cap 13 has a solid bottom wall 17 with a sufficient vertical wall 18 extending upwardly therefrom to embrace the lower portion of the fire extinguisher 10 as shown in Fig. 2. The upper cap 14 has a top wall 19 which has a central opening 20 formed therein to permit clearance therethrough of a collar 21 forming a part of the fire extinguisher. As seen in Fig. 1 the conventional hand type extinguisher has a T-shaped handle 22 extending upwardly from the collar 21. To facilitate ease in mounting the upper cap 14 on the extinguisher 10 I have provided an elongated shape to the opening 20 by forming a pair of oppositely disposed recesses 23 in the top wall 19. By thus shaping the opening 20 the cap 14 can be placed over one arm of the T-shaped handle 22 and then be shifted sidewise for passage over the other arm of the T-shaped handle. The upper cap 14 has a depending skirting 24 which is adapted to embrace the upper side walls of the extinguisher 10 in the manner shown in Fig. 2. By these upper and lower caps 14 and 13 it will be noted that both filler cap 14' and lower cap 13', both of which are removable, are completely enclosed and cannot be removed from the cylindrical portion 10' without also removing the sealing caps 13 and 14.

Means for maintaining the upper and lower caps 14 and 13 in the aforementioned position on the fire extinguisher 10 is provided in the form of a lead seal 25. Each cap 13 and 14 has

a vertically extending tab 26 having a hole 27 punched therethrough. The lead seal 25 comprises a piece of wire 28 or other binding means which is threaded through the holes 27 in the tabs 26 as shown in Fig. 3, the two free ends 5 29-30 of the wire element 28 being joined by a lead ball 31 in a well-known manner.

When the safety seal is completely mounted upon the extinguisher 10 as hereinbefore explained it appears as shown in Fig. 1 wherein the 10 nozzle 32 of the extinguisher 10 is completely covered against access by reason of the solid bottom wall 17 on the lower cap 13 and only the handle 22 of the upper portion of the extinguisher is accessible for gripping. Thus it is seen that 15 I have provided a safety seal for fire extinguishers whereby to prevent removal of the filler cap 14' without breaking the seal 25; also that the nozzle 32 is guarded so that foreign matter cannot be inserted therewith. Any rupture of the fibre 20 structure of either upper or lower caps 14 or 13 can be easily seen by the most cursory examination. For this reason persons responsible for the condition of the fire extinguisher will be more 25 careful in seeing that it is in perfect working order.

When an emergency arises and the extinguisher must be used it is only necessary to pull the wire 28 and thus rip the tabs 26 thus freeing the lower 30 cap 13 for removal to permit ejection of fluid from the nozzle 32.

Although fire extinguishers of the hand type are usually standard in dimensions there are slight discrepancies in fittings such as the lower caps 13' and the filler caps 14'. To compensate 35 for such discrepancies I provide expansion means in the formation of the caps 13 and 14 by forming a vertical pleat 33 in the walls thereof at spaced intervals. By reason of such construction there will be a certain amount of elasticity in 40 the body of caps 13 and 14 so that they will fit snugly around the fire extinguisher as shown in section in Fig. 2.

A modified construction of my sealing caps 13 and 14 is shown in Figs. 6 through 8 wherein a 45 top cap is indicated by the reference numeral 34 and a lower cap by number 35. These caps 34 and 35 have the same body structure as my preferred form and are indicated by like reference characters but differ from the preferred form only by reason of being made of corrugated paper 50 36 to provide contiguous vertical pleating completely around the cap. As seen in Figs. 6 and 7 the opening 20 in the top wall 19 of the upper cap 14 need not be recessed as at 23 in Fig. 4. This is so by reason of the pliability of corrugated paper which when the cap 34 is mounted 55 over the handle 22 can be distorted to an elongated opening to fit over the handle 22. This form of cap is also more suited for extinguishers 60 of a slightly larger diameter and are economical in manufacture.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modification as come within the 70 scope of the appended claims.

Having thus described my invention, what I claim as new and desire to protect by Letters Patent is:

1. In a safety seal for a hand type fire extinguisher having a nozzled bottom end and a pump handle extending from its upper end, said safety seal comprising a cup shaped bottom seal adapted to be arranged over said nozzled bottom end to completely embrace the same, an inverted cup shaped top seal having an opening formed in its top wall and adapted to fit over the pump handle to cover the upper end of the fire extinguisher, and means for sealing said bottom seal and top seal in the position aforesaid.

2. In a safety seal for a hand type fire extinguisher having a nozzled lower end and a removable upper end having a pump handle extending therefrom, said safety seal comprising a paper cap having a solid bottom wall disposed over said nozzled lower end and a second paper cap having an opening formed in its upper wall and adapted to cover said removable upper end and permit said pump handle to extend therefrom, and a lead seal for maintaining said paper caps in the positions aforesaid.

3. In a safety seal for a hand type fire extinguisher having a nozzled lower end and a removable upper end having a pump handle extending therefrom, said safety seal comprising a paper cap having a solid bottom wall disposed over said nozzled lower end and a second paper cap having an opening formed in its upper wall and adapted to cover said removable upper end and permit said pump handle to extend therefrom, and a lead seal for maintaining said paper caps in the positions aforesaid, said paper caps having pleats formed therein to render said caps flexible for fitting over said fire extinguisher as aforesaid.

4. In a safety seal for a hand type fire extinguisher having a nozzled lower end and a removable upper end having a pump handle extending therefrom, said safety seal comprising a paper cap having a solid bottom wall disposed over said nozzled lower end and a second paper cap having an opening formed in its upper wall and adapted to cover said removable upper end and permit said pump handle to extend therefrom, and a lead seal for maintaining said paper caps in the positions aforesaid, said paper caps being formed of corrugated paper to render them adjustable to variations in configurations of said fire extinguisher.

5. In a safety seal for a hand type fire extinguisher having a nozzled lower end and a removable upper end having a pump handle extending therefrom, said safety seal comprising a paper cap having a solid bottom wall disposed over said nozzled lower end and a second paper cap having an opening formed in its upper wall and adapted to cover said removable upper end and permit said pump handle to extend therefrom, and a lead seal for maintaining said paper caps in the positions aforesaid, said paper caps being formed of corrugated paper to render them adjustable to variations in configurations of said fire extinguishers, and to permit of facile removal thereof by tearing.

FRED FREDRIKSEN.
